BY *Nicetor J. Evans*
HIS ATTORNEY

UNITED STATES PATENT OFFICE

JOHN M. WOYTHAL, OF CHICAGO, ILLINOIS

SCISSORS

Application filed April 15, 1929. Serial No. 355,213.

This invention relates to certain novel improvements in scissors and more particularly with reference to the connection between the blades thereof and has for its principal object the provision of an improved construction of this character which will be highly efficient in use and economical in manufacture.

Among the several objects of this invention is to provide an effective connection between the blades of a scissors whereby the blades will be held in close proximity with respect to each other thereby assuring a more efficient and positive cutting connection of the blades when manipulated.

A still further object of the invention is to provide a connection between the blades of a scissors whereby play between the blades of the scissors may be conveniently and expeditiously taken up without dismantling or disconnecting the blades of the scissors.

Other objects will appear hereinafter.

The invention consists in the combination and arrangement of parts hereinafter more fully described and claimed.

The invention will be best understood by reference to the accompanying drawings, showing the preferred form of construction, and in which:

Fig. 1 is a perspective view of a scissors embodying the invention;

Fig. 2 is a fragmentary sectional detail view of the same taken substantially on line 2—2 of Fig. 1; and

Fig. 3 is a fragmentary sectional detail view taken substantially on line 3—3 of Fig. 2.

In attaining the objects of the invention herein set forth it is also an additional object of the invention, which results from the simplicity of the construction of the invention, to provide a connection between the blades of a scissors which may be easily adjusted by one other than a mechanic or a person skilled in the art. To accomplish this and other objects of the invention and to further understand the utility of the invention I will first describe the parts which comprise an ordinary scissors of a conventional type.

A scissors of the ordinary conventional type includes two blade members 10 and 11.

These blade members include handles 12 whereby to effectively operate the blades. The blade members 10 and 11 are arranged in a position for shearing or cutting connection relatively to each other and are provided with the usual cutting edges 13.

To accomplish the many objects of my invention I provide in each of the blade members at a portion which I desire to term the hub 14, openings 15 which register with each other when the blade members are arranged in the position illustrated in Fig. 2.

Preferably though not necessarily from a short piece of tube I provide a sleeve 16 which is adapted when positioned in the openings 15 to snugly fit in such openings. The inner end portion of the sleeve has its end edges 17 turned inwardly to provide an annular shoulder 18 defining a central opening 19. The outer edges 21 of the sleeve are turned outwardly to provide a bearing bead 22 which bears against the adjacent surface 23 of the adjacent hub 14.

Preferably though not necessarily from a short piece of tube I provide a second sleeve 24. This sleeve 24 is of a diameter which permits insertion of the sleeve through the opening 19 whereby to dispose its inner end a short distance from the plane of the outer end of the sleeve 16 as at 25. The outer end of this sleeve is likewise turned over to provide a bearing bead 26 which is adapted to bear against the adjacent surface 27 of the adjacent hub 14. The sleeve 24 when inserted through the opening 19 into the sleeve 16 provides a stud around which is removably mounted an expansion spring 28. This expansion spring 28 is held in place and compressed against the seat 18 by means of a screw element 29 inserted into the inner end of the sleeve 24.

While I have shown in the drawing that the spring is compressed and retained in position by a screw element it is obvious that this screw element may be in the form of a head bearing rivet sweated or otherwise fitted into the sleeve 24, or may be a head formed on the stud.

From the description herein set forth it will be manifest that by the provision of the

expansion spring one end will bear against the shoulder 18 and the other end against the head 30 of the screw element 29 and when compressed will effect a frictional fit between 5 the two blades of the scissors whereby to provide a more efficient shearing or cutting action when the blades are manipulated.

It will be seen from the description herein taken in connection with the accompanying 10 drawing that the parts may be easily adjusted or taken apart as may be required.

While I have illustrated and described the preferred form of construction for carrying my invention into effect, this is capable of 15 variation and modification, without departing from the spirit of the invention. I, therefore, do not wish to be limited to the precise details of construction set forth, but desire to avail myself of such variation and 20 modifications as come within the scope of the appended claims.

Having thus described my invention what I claim as new and desire to protect by Letters Patent is:

25 1. Means for providing a connection between two cooperating cutting elements having registering openings comprising two members arranged in opposing relation with respect to each other inserted in said openings 30 and each provided with an enlarged head adapted to bear against adjacent surface of the cutting elements, one of said members being formed at its end opposite its head to provide a shoulder, a resilient member 35 mounted between said members and having one end engaging the shoulder, and means carried by the other of the members for comprising said resilient member so as to yieldably urge said members toward each other 40 and bear the heads thereof against said adjacent surfaces.

2. Means for providing a connection between two cooperating cutting elements including a resilient member, and two members arranged in telescopic relation with respect to each other and inclosing said resilient member and having enlarged portions bearing against adjacent surfaces of the cutting elements and means cooperating with 50 one of said members and with said resilient member to provide a connection between said members, said means also being adapted to compress said resilient member in holding said members in said connected relation.

55 In testimony whereof I affix my signature.
JOHN M. WOYTHAL.
